Primary Examiner — Keli L Hill*Assistant Examiner* — Sara S Sahneh(74) *Attorney, Agent, or Firm* — Baumgartner Patent Law; Marc Baumgartner(57) **CLAIM**

The ornamental design for pliers, as shown and described.

DESCRIPTION

FIG. 1 is a front perspective view of pliers embodying my new design;

FIG. 2 is a second front perspective view of the pliers of FIG. 1;

FIG. 3 is a front-side view of the pliers of FIG. 1, the rear-side view is a mirror image;

FIG. 4 is a left-side view of the pliers of FIG. 1;

FIG. 5 is a right-side view of the pliers of FIG. 1;

FIG. 6 is a top-side view of the pliers of FIG. 1; and,

FIG. 7 is a bottom-side view of the pliers of FIG. 1.

The broken lines show portions of the article not claimed and form no part of the claimed design.

1 Claim, 5 Drawing Sheets(56)
